UNITED STATES PATENT OFFICE.

JOSEPH DONAY, OF CLEVELAND, OHIO.

COMBINATION CURTAIN AND SHADE HOLDER.

Application filed May 29, 1925. Serial No. 33,623.

This invention relates to improvements in curtain and shade holders, particularly devices of this type which are adapted to fit any width of window frame.

5 It is the principal object of the invention to provide a window shade and curtain mounting, adapted to support both, the usual shade roller and the rod or rods from which curtains or draperies or the like are suspended, and one, which allows an adjustment and locking of the parts in their adjusted positions.

10 Another object of the invention is the provision of a combination window shade and curtain mounting allowing a folding of the shade roller support to make the mounting convenient for storing and packing.

15 A further object of the invention is the provision of a readily displaceable bracket 20 for the shade roller support within certain limits.

25 A still further object of the invention is the provision of a device of this character which is simple and inexpensive in its construction, and which can readily be attached to a window frame or the like.

30 For further comprehension of the invention and its many objects and advantages, reference will be had to the following description and accompanying drawing, and to the appended claims in which the various novel features of the invention are more particularly set forth.

In the drawing:

35 Fig. 1 is a perspective view of the combination curtain and shade holder constructed according to the present invention.

Fig. 2 is a front elevation thereof.

Fig. 3 is a top plan view of the device.

40 Fig. 4 is a detail side elevation of the shade roller support, partly in section on line 4—4 of Figure 2.

45 My improved window curtain and shade mounting comprises a pair of brackets or supports located at opposite sides of the window frame near the top thereof. These brackets or supports being respectively of right and left hand construction, but otherwise the same so that the description of one will be sufficient for the understanding of the invention.

50 Each of these mountings comprises a base or supporting plate 10 equipped at one side thereof with a flange angularly disposed to the plate 10 and designated 11. Both the flange, as well as the plate are provided with

openings allowing the passage of the suitable fastening means for attaching the device to the side edges and the front of a window frame, as shown at 12.

60

Two parallel longitudinal guides 13 and 14 are provided on the body of the plate 10 closer to the lower edge thereof than to the upper one, to form guides for the upper and lower flanges 15 and 16 of the base 16' of the shade roller holder 17 for firmly guiding the base 16' during its displacement longitudinally to plate 10. In the area limited by the guides 13 and 14 the plate 10 is provided with corrugations, as shown at 15' for a purpose hereafter more fully to be described.

65

To the base 16' are attached, or made integrally therewith, the two forwardly extending cheeks, 22, 23 engaging the side faces of the holder 17 on opposite sides thereof. The shank of the holder 17 is extended to the rear between the two cheeks and is intermediate its ends pivotally secured to the same by means of the pin 24. The holder 17 has the customary upper frontal slot 25 for the reception of the roller pinnacles, and has a rear extension 26, adapted to pass in the operating position of the holder through the slot 21 in base 16' into engagement between the teeth or corrugations 27 provided for at the front face of the plate 10 to lock the holder 17 firmly in any of its adjusted positions with respect to the guide. The holder 17 furthermore, has near its rear 70 end an upper nose or extension 30 passing through slot 21 when the holder is folded against plate 10 by turning it about its pivot, while its outer slotted part is extending through a vertical slot 31 in plate 10 above slot 13 therein.

75

75 Two removable tubular stems 32 and 33 are securely held in their working positions in any suitable manner in suitable openings of the plate 10 near the upper left hand corner thereof, and are adapted to receive the ends of an extensible curtain rod or pole in the well known manner.

80

85 The operation of the device will be entirely clear from the above description, the flanges 15 and 16 are passed into the guides 13 and 14, the corrugations 27 on plate 10 are engaged by teeth on the rear extension 26 of the holder 17 when the same is in its operating position. If the device is ready 90 for packing, the holder 17 is swung about its pivot so that its upper or outer slotted

105

110

end is guided against plate 10 and through the slot 31 therein, while the tubular stems 32 and 33 are removed, thus allowing a convenient stacking of the mountings so as to 5 take up as little space as possible.

The recess 25 allows the support of the pintles of a shade roller on holder 17 in the usual manner, while the open front ends of the tubular stems 32, 33 allow the introduction of the suitably bent ends of extensible curtain rods or poles.

It is to be understood that many changes may be made in the construction of the minor details of my device without departure from the scope of the invention as 15 defined in the appended claims and without conflicting with the spirit of my invention.

Having thus described my invention, what I claim as new and desire to secure by Letters Patent is as follows:

1. In a device of the class described, having a shade roller holder formed with a rear extension engageable with vertical corrugations between longitudinal guides, the combination of a base, an upper and lower flange 25

depending from said base, and engageable beneath said longitudinal guides, forwardly extending cheeks projecting from said base, and formed with aligned apertures to pivotally hold said shade roller holder, and said base being formed with a slot to permit the said rear extension of said shade roller holder to engage the said vertical corrugations.

2. In a device of the class described, having a shade roller holder formed with a rear extension engageable with vertical corrugations between longitudinal guides, the combination of a base, an upper and lower flange depending from said base, and engageable beneath said longitudinal guides, forwardly extending cheeks integral to said base, and formed with aligned apertures to pivotally hold said shade roller holder, and said base being formed with a slot to permit the said rear extension of said shade roller holder to engage the said vertical corrugations.

In testimony whereof I have affixed my signature.

JOSEPH DONAY.
